CAKE WASHING AND CONDITIONING
MACHINE

John Joseph Sippel, Upper Darby, Pa., assignor
to H. W. Butterworth & Sons Company, Philadelphia, Pa., a corporation of Pennsylvania

Application December 13, 1932, Serial No. 647,068

11 Claims. (Cl. 18—8)

This invention relates to a cake-washing and conditioning machine, and more particularly to an apparatus for the continuous treatment of rayon cakes to prepare the same for use.

5 As is well known to those familiar with the art, rayon cakes, in their original state, contain foreign substances which must be removed prior to use of the yarn. This is, ordinarily, accomplished by unreeing the cake and skeining the yarn and 10 then putting the yarn through the various processes necessary to properly condition the same. This conditioning involves treatment of the yarn by a plurality of fluids with the resultant necessity for frequent handling of the skeins which 15 become tangled and the threads of which are often broken or otherwise rendered unfit for use.

An important object of this invention is the provision of a structure by means of which the rayon cake, *per se*, may be continuously carried 20 through the various conditioning stages and successively subjected to the different treatments without handling.

A further and more specific object of the invention is the provision in an apparatus of this 25 character of a construction such that a header, with which the cakes are interiorly connected, may be successively passed through a plurality of stations, at each of which a fluid employed in the treatment is introduced to the header, and may 30 be automatically connected with a source of supply of the treating fluids in such stations upon its arrival at the station and without the necessity of manual operations.

A further object of the invention is the provision in apparatus of this character of an arrangement such that the header can be securely 35 connected by a fluid-proof connection to the source of supply at each of a series of stations by automatic means.

40 A still further object of the invention is the provision of novel and improved apparatus for successively progressing the headers through such stations and for handling the headers when they have completed their travel through the 45 stations.

These and other objects I attain by the construction shown in the accompanying drawings wherein, for the purpose of illustration, I have shown a preferred embodiment of my invention, 50 and wherein:

Figs. 1 and 1a comprise a side elevation of a rayon cake-conditioning machine constructed in accordance with my invention;

Fig. 2 is a semi-diagrammatic plan view of 55 the apparatus;

Fig. 3 is a section on line 3—3 of Fig. 1;

Fig. 4 is an enlarged sectional view similar to that shown in Fig. 3 illustrating the construction of the cake mountings and of the fluid inlet for the headers;

Fig. 5 is a section on line 5—5 of Fig. 4;

Fig. 6 is an enlarged fragmentary plan view of the apparatus;

Fig. 7 is an enlarged plan view of one of the 10 headers;

Fig. 8 is a diagrammatic view illustrating the 15 control apparatus regulating progression of the headers through the various treating stages;

Fig. 9 is a vertical sectional view through the 20 control valve;

Figure 10 is a horizontal sectional view there- 25 through; and

Fig. 11 is a sectional view through the cycle 30 valve.

Referring now more particularly to the drawings, the numerals 10 and 11 generally designate 20 side members supported by spaced standards 12. The side members between each pair of standards support drip pans 13, the discharge of which is led to either a fluid storage or a drain, depending 25 upon the character of the treating fluid at the particular station. Side members 10 and 11 likewise support spaced parallel tracks 14 and 15, of which the track 14 is shown as directly carried by the side member, and the track 15 is supported 30 therefrom through an overhanging bracket 16.

In alignment with each pan, the side member 10 has mounted therein a fluid inlet nozzle 17 supplied from a motor-operated pump 18. While Fig. 1 illustrates pumps as applied at only three 35 of the stations, it will be understood that each of the stations is so equipped, as more clearly shown in Fig. 2, with the exception of the final or drip station of the apparatus. The opposite side member 11 is equipped at each of the stations 40 with the exception of the drip station, with a hydraulic ram 19, the purpose of which is present- 45 ly to appear. There may be as many stations between the entry station and the drip station as desired, the number of stations provided depend- 50 ing upon the type of treatment employed for the yarn. It will, of course, be understood that in some methods of treatment a greater variety of treating fluids is employed than in others, and while it is, ordinarily, necessary to wash the 55 cakes after each station at which a treating fluid is introduced, the washing may in some instances be omitted. The stations illustrated in Figs. 1 and 1a will, therefore be understood as merely 55 illustrative and not limiting.

- At each of the side members 10 and 11, and at the entry and drip stations, sprockets or chain wheels 20 are provided, about which is trained a chain, or other suitable flexible element indicated at 21. Each side member bears a hydraulic traverse cylinder 22 connected through slides 23 with the ends of the chain 21 of the side member, these connections permitting adjustment, as indicated at 24. The upper run of the chain, or that portion thereof extending between the upper peripheral portions of the chain wheels 20, bears a series of dogs 25 corresponding in number to the number of stations, disregarding the entry station.
- With a foundation structure of this character, I employ a plurality of headers 26, these being provided in number sufficient to insure a constant supply at the entry or receiving end. Each header comprises a hollow body 27 having in its upper wall a series of openings 28. The sides of the header, through projecting brackets 29, engage the lower ends of links 30 pivotally suspended from carriages comprising bars 31 supported at their opposite ends by pairs of rollers 32 and 33 engaging the tracks 14 and 15 respectively. It will be noted that through this suspension the header is capable of transverse movement between the side members.
- Each header, at that side thereof opposed to the side member 10, is provided with an extended inlet 34 adapted for co-action with the flared mouths of nozzles 17. The outer ends of these inlets are provided with soft gaskets 35 adapted to engage the inner end of the nozzle fitting about the opening thereof so that a perfect seal may be established. Each header, at its opposite side and adjacent the side member 11, has a striker plate 36 for engagement by the ram 19.
- It will be obvious that when a header is disposed in any particular station and the ram 19 thereof actuated, it will engage the header, forcing the same transversely between the side members and bringing the sealing element 35 into sealing engagement with the inner end of the nozzle fitting so that a fluid-tight connection is provided and fluid under pressure can be pumped into the header by the pump of the station.
- In order that the header may be moved to the successive stations, each header has a latch element 37 for co-action with the lugs 38 of the chains 21, these latch elements being pivoted so that when chains 21 at their upper runs are moved toward the entry or charging end, the lugs of the chain will pass under the latch elements without effect thereon, but when the chain is moved in the direction of the arrow, the lugs will engage the latch elements moving the headers mounted on the machine through a step, the length of which is determined by the extent of movement of the ram of traverse cylinder 22, thus shifting the header through a distance equivalent to the space between adjacent stations.
- Rayon cakes are mounted upon the headers in the manner more particularly shown in Fig. 4. Each cake is placed upon a mounting comprising an inner perforated cylindrical wall 39 provided at its lower end with a flange 40 which is defined by an upstanding rim 42 and a downwardly-extending shoulder 43. As shown in this figure, the cakes C are usually of tapered form and shoulder 43 is formed on such a diameter that it will engage about the upper or smaller end of the cake, while the shoulder 42 will engage about the larger or lower end of the cake.
- The inner cylindrical wall is of such diameter that it will fit about the outlets 28 and the lowermost cake is placed in this position while the remaining cakes are stacked thereon until the stack attains a desired height. A cap plate 44 is then placed on the stack. Each header has hinged hold-down plates 45 which may be swung to position over top of the cakes and held in this position through pivoted latches 46. Each hold-down plate is equipped with a pressure screw 47 aligned with each stack of cakes and adapted to engage against the cap plate 44 of the stack. It will be obvious that when the cakes are stacked upon the header they will be very securely held and will be disposed with their interiors in communication with the interior of the header; consequently, if liquid is forced into the header, it will pass through the cakes washing or treating the same and then pass downwardly over the header and into the drip pan 13 of the station at which the header is located. The side members 10 and 11 are preferably provided at their inner faces with rubber splash guards 48 to prevent the treating liquids from coming into contact with the mechanism to any more than the necessary extent.
- The operation of the several elements hereinbefore described is coordinated by means of the apparatus diagrammatically shown in Fig. 8. In this figure, the numeral 49 designates a distributing valve having a pressure fluid inlet port 50 communicating through a conduit 51 with the discharge of a pump 52, which pump receives its supply from a sump 53. The valve further includes an exhaust fluid outlet port 54 communicating through a conduit 55 with sump 53. The valve element 56 of this valve is controlled through solenoids 57 and 58 and acts to alternately place conduits 59 and 60 in communication with the pressure fluid inlet and the exhaust fluid outlet. Conduit 59 communicates with all of the cylinders 19 of rams 18 to deliver fluid pressure to these rams in the operative stroke of the rams, while conduit 60 communicates with all of these cylinders to deliver fluid pressure to the rams in the withdrawal stroke of the rams. Conduit 59 communicates with corresponding ends of traverse cylinders 22 through a branch conduit 61 containing a cycle valve 62 while conduit 60 communicates with the opposite ends of these cylinders through a branch conduit 63 containing a cycle valve 64. Cycle valves 62 and 64 each comprise a cylinder 65 having an inlet port 66 adjacent one end, an exhaust port 67 adjacent the opposite end, and an outlet port 68 midway between its ends. A piston 69 within the cylinder is normally so positioned by a spring 70 that it cuts off flow between inlet port 66 and port 68 and establishes a flow connection between exhaust port 67 and the port 68. When fluid under pressure is admitted at port 66, and the accrued pressure becomes sufficient to shift the valve, the valve is shifted to a position where it establishes communication between ports 66 and 68 and cuts off communication between ports 67 and 68. The port 66 is, in each instance, connected with the conduit 59 or 60 with which the valve is associated, the port 67 with the return line 55, and the port 68 with the cylinders. Solenoids 57 and 58 are controlled through a suitable timing device 71 to provide an operation substantially as follows: Assume the treating apparatus hereinbefore described to be loaded and each station thereof occupied by a header supporting rayon cakes under treatment. At the end of the treating period, fluid is delivered through conduit 60 to the inner ends of ram 75

cylinders 19a withdrawing these rams and permitting the headers 26 to move through the supporting links thereof to a position where the headers are freed of all contact with the side members other than through their supporting carriages. When the rams are fully withdrawn, pressure builds up in conduit 60 with the result that the piston 69 of valve 64 is elevated and pressure is delivered to the left hand ends of traverse cylinders 22 in Fig. 8. This pressure moves the rams of the traverse cylinders, and through the rams and chains 21 moves all of the headers 26 through a distance of one station. Timing device 71 then operates to reverse the position of valve 49 so that pressure fluid is now delivered through conduit 59 to the outer ends of the ram cylinders 19a. The rams of the cylinders are projected, engaging the striker plates 36 of the several headers and moving the headers transversely until the inlets thereof come into sealing engagement with the mouths of nozzles 17. With the completion of this movement, pressure builds up in conduit 59, the piston 69 of cycle valve 62 is elevated and pressure is delivered to the right hand ends of cylinders 22 in Fig. 8. The chains are thus reversely shifted without moving the headers and positioned for a second stroke. During the stroke of the pistons of the cylinders 22, exhaust fluid passes through the proper cycle valve 64 by way of ports 68 and 67 thereof to the sump. With the arrival of headers at a new station and the actuation of solenoid 57 to position the valve 49 for distribution of fluid pressure to conduit 59, the pump motors of treating fluid supply pumps 18 are actuated to provide delivery. These pumps are usually of the centrifugal type and there is a sufficient discharge lag upon initial operation thereof to enable the rams 19 to perform their function prior to delivery of fluid at the nozzles 17. The treating period is fairly extended, and it will, of course, be obvious that pressure delivered to the ram cylinders 19a must be continuous during this operation. For this reason, the discharge line 51 of pump 52 has a relief valve 72 permitting the discharge from this pump to pass to the sump after a predetermined pressure has been generated in the discharge line.

It will be obvious that with apparatus of this character, treatment of the cakes is materially facilitated in that there is no handling either of the cakes or the headers on which they are supported from the time of their delivery to the machine until the treating operation is completed, all operations in passing the headers from one station to another being automatic and connections with the treating fluid supplies at such stations being likewise automatic.

It will also be obvious that with apparatus of this character the same power employed to cause station-to-station movement of the headers may, likewise, be employed to deliver these headers upon trucks 73 through which they may be shifted through unloading and loading stations and returned to the loading or empty end of the machine. A convenient truck for this purpose comprises a wheel-supported frame 74 having track elements 75 provided at their opposite ends with clamping means 76 for engagement with the ends of the members 10 and 11 to insure alignment of the track elements 75 with the track elements of these members.

As the apparatus described is capable of considerable modification without in any manner departing from the spirit of my invention, I do not

wish to be understood as limiting myself thereto except as hereinafter claimed.

I claim:

1. In a machine of the character described, a row of nozzles, a header having an inlet, means supporting the header for movement along said row of nozzles in spaced relation to said nozzles, means for intermittently moving the header from one nozzle to another, and means for transversely shifting the header to bring the inlet of the header into sealing engagement with each nozzle when the header is aligned therewith. 5

2. In a machine of the character described, a row of nozzles, a header having an inlet, means supporting the header for movement along said row of nozzles in spaced relation to said nozzles, means for intermittently moving the header from one nozzle to another, means for transversely shifting the header to bring the inlet of the header into sealing engagement with each nozzle when 15 the header is aligned therewith, and timing means coordinating operation of said moving means and said shifting means. 20

3. In a machine of the character described, a row of nozzles, a header having an inlet, means supporting the header for movement along said row of nozzles in spaced relation to said nozzles, means for intermittently moving the header from one nozzle to another, means for transversely shifting the header to bring the inlet of the header 25 into sealing engagement with each nozzle when the header is aligned therewith comprising a ram associated with each nozzle and arranged at the opposite side of the path of movement of the header from the nozzle, and means for actuating 30 the ram when the header is between the ram and its associated nozzle. 35

4. In a machine of the character described, a row of nozzles, a header having an inlet, means supporting the header for movement along said row of nozzles in spaced relation to said nozzles, means for intermittently moving the header from one nozzle to another, means for transversely shifting the header to bring the inlet of the header into sealing engagement with each nozzle when 45 the header is aligned therewith comprising a ram associated with each nozzle and arranged at the opposite side of the path of movement of the header from the nozzle, means for actuating the ram when the header is between the ram and its 50 associated nozzle, and means for alternately operating said moving means and said rams.

5. In a machine of the character described, a row of nozzles, a header having an inlet, means supporting the header for movement along said row of nozzles in spaced relation to said nozzles, automatic means for intermittently moving the header from one nozzle to another, and automatic means for transversely shifting the header to bring the inlet of the header into sealing engagement with each nozzle when the header is aligned therewith. 55

6. In a machine of the character described, a row of nozzles, a header having an inlet, means supporting the header for movement along said row of nozzles in spaced relation to said nozzles, automatic means for intermittently moving the header from one nozzle to another, and automatic means for transversely shifting the header to bring the inlet of the header into sealing engagement with each nozzle when the header is aligned therewith comprising a ram associated with each nozzle and arranged at the opposite side of the path of movement of the header from the nozzle, and means for actuating the ram 70 75

when the header is between the ram and its associated nozzle.

7. In a machine of the character described, a row of nozzles, a header having an inlet, means supporting the header for movement along said row of nozzles in spaced relation to said nozzles, means for intermittently moving the header from one nozzle to another, means for transversely shifting the header to bring the inlet of the header into sealing engagement with each nozzle when the header is aligned therewith, means for supplying treating fluids to said nozzles, means rendering the supply means of each nozzle operative as the header is brought into sealing engagement therewith, and timing means coordinating operation of said moving, shifting and supply means.
8. In a machine of the character described, a row of nozzles, a header having an inlet, means supporting the header for movement along said row of nozzles in spaced relation to said nozzles, hydraulically operated means for intermittently moving the header from one nozzle to another, hydraulically operated means for transversely shifting the header to bring the inlet of the header into sealing engagement with each nozzle when the header is aligned therewith, a single supply means for said hydraulically operated means, and means to delay operation of the intermittent moving means until the shifting means has released the header from a previously engaged inlet.
9. In a machine of the character described, parallel tracks, a carriage on each track, a header below the carriages, a link suspended from each carriage and supporting the associated header for movement in a direction transverse to the

tracks, means for intermittently moving the carriages along the tracks, a series of nozzles arranged at one side of the tracks, and means to engage the header and transversely move the same when the inlet of the header comes in alignment with a nozzle.

10. In a machine of the character described, parallel tracks, a carriage on each track, a header below the carriages, a link suspended from each carriage and supporting the associated header for movement in a direction transverse to the tracks, means for intermittently moving the carriages along the tracks, a series of nozzles arranged at one side of the tracks, means to engage the header and transversely move the same when the inlet of the header comes in alignment with a nozzle, and means to coordinate operation of said carriage moving and header moving means.

11. In a machine of the character described, parallel tracks, a carriage on each track, a header below the carriages, a link supported from the carriages for movement in a direction transverse to the tracks, said header having an inlet, a series of nozzles adjacent one side of the tracks, means to engage the header and move it transversely when it comes into alignment with a nozzle, and means for intermittently shifting the carriages to bring the header inlet into alignment with the nozzles, comprising a longitudinal reciprocable member associated with each track, and co-acting means upon the reciprocable member and said carriages, whereby the carriages are advanced upon each movement of the members in one direction.

JOHN JOSEPH SIPPEL.
